COTTON DRAWING FRAME

Erich Langen, M.-Gladbach, Germany

Application January 19, 1934, Serial No. 707,323

2 Claims. (Cl. 19—131)

In cotton drawing frames with pairs of drawing rollers, six or eight carded slivers are generally fed close together side by side to the pair of feeding rollers and after the drawing, the fleece is united to form a single sliver which is then caught in a can. This doubling six or eight times necessitates a great width of the drawing rollers, wherefrom results that the fibres are not reliably guided at the sides of the fleece and consequently irregularities in the delivered sliver are caused. Therefore, it has already been proposed to separately draw the slivers on cotton drawing machines and to unite them only behind the delivery rollers.

With regard to the high draft this has hitherto been used successfully only in fine spinning machines and flyers. It has already been proposed, to employ it in cotton drawing frames, in which instance one conveyor band for high drafting, of correspondingly large width, was selected for all the slivers to be doubled, that is for six to eight slivers. The great width of the conveying bands is, however, the reason that crooked running soon occurs so that the conveying bands wear on one side in a very short time and become useless. Moreover, the extraordinary width of the conveyor band places such high requirements on the leather as regards uniformity of density and stretching, that it is practically impossible to procure the same.

According to the invention one system of high drafting is provided for each sliver, or for example for two slivers of one supply, and the slivers of one supply thus drawn are doubled to form a single sliver after leaving the delivery rollers. By this subdivision an improvement in the guiding of the fibres is attained, because for example only a few slivers are doubled and drawn per subdivision. The slivers of several subdivisions thus drawn are then united to form one single sliver.

Two embodiments of the invention are illustrated in the accompanying drawing in which:—

Fig. 1 shows in side elevation a cotton drawing frame for high drafting with conveyor bands.

Fig. 2 is a top plan view of Fig. 1.

Fig. 3 is a front elevation of Fig. 1.

Fig. 4 shows the conveyor band guide pulleys in side elevation on a larger scale.

Fig. 5 is a front elevation showing a high drafting system by means of fluted rollers.

By means of a pair of feed rollers, *b*, *c* and a sliver distributor *d* the cotton slivers *a* are fed singly or with slight doubling to the drafting mechanism which consists of pairs of rollers *e*, *f*.

g, *h*. An independent high drafting frame comprising two endless bands *i* is arranged between the pairs of rollers *g* and *h* for each sliver or, according to Fig. 2, for example, for every two slivers. Behind the pair of front rollers *h* the separately drawn slivers are again united to a single one in the delivery funnel *m*.

As can be seen from Figs. 1 to 3 the guide cage for the three pairs of conveyor bands of one supply is made in one piece. It consists of longitudinal bars *n* and transverse walls *o* cast or otherwise fixed thereon. The rollers *g* have turned grooves *p*, Fig. 2, in which the transverse walls *o* with slots *q* are secured against lateral displacement. Pulleys *r* and *s* serve for the front guiding of the conveyor bands *i*, *k*. The upper pulleys *r* of a delivery are loosely mounted on a common rod *t*, whereas the lower pulleys *s* are each loosely mounted on a guide rod *u*, so that they can be easily removed from the cage. The rods *t* and *u* are secured against lateral displacement in some suitable manner. The pulleys *r* and *s* cannot shift in lateral directions because they are each situated between two cage walls *o*.

The upper guide pulleys *r* for the conveyor bands *i* of a delivery are jointly weighted. For this purpose saddles *v* rest on the rods *t* and are weighted by a common weight *w*. To have the weight distributed uniformly on all conveyor bands, the following arrangement is provided. A cord *x* engages the two outer saddles *v*' and is guided over pulleys *y* of an intermediate element *z* and pulleys *2* of the middle saddles *v*.

Fig. 5 shows the employment of a fluted drawing frame according to the invention, wherein, exactly as in Fig. 2, a few, for example two, of the supplied slivers are guided by subdivided fluted cylinders *3*, *4*, *5* arranged side by side, and are doubled to form a single sliver behind the pair of front rollers. Any other system of high draft may be employed instead of the conveyor bands or grooved drawing frame, as mentioned above.

I claim:—

1. A frame for drawing and doubling cotton slivers, comprising in combination with a plurality of feed and delivery rollers, high drafting arrangements comprising endless bands, one for each of the supplied slivers, and a cage, upper and lower guide pulleys on said cage, a common weight loading the upper guide pulleys, an element intermediate the weight and guide pulleys and from which the weight is suspended, cord and pulley connections between the upper guide pulleys and the intermediate element and means

beyond said plurality of rollers for uniting said highly drawn slivers.

2. A cotton drawing frame for drawing and doubling cotton slivers, comprising in combination with supply rollers and delivery rollers, one system of high draft for each of the supply slivers comprising endless bands and a cage supporting said bands, said bands adapted to double the slivers supplied from the rear roller to the delivering roller so that a single sliver is formed by the doubled slivers leaving the delivering rollers, an upper and lower transverse rod in the front end of said cage secured against rotation and against shifting in lateral direction, upper 5 guide pulleys and lower guide pulleys on said

cage and loosely mounted on said transverse rods, a common weight loading all said upper guide pulleys, saddles resting on said upper transverse rod one between every two guide pulleys, pulleys attached one to the lower end of each 5 of said saddles with the exception of the two extreme saddles, an intermediate element, pulleys on said intermediate element, a cord attached with its ends to said extreme saddles and guided over said pulleys on said intermediate element 10 and over said pulleys attached to said inner saddle, and a weight attached to the middle of said intermediate element adapted to uniformly load all said saddles.
